UNITED STATES PATENT OFFICE.

WILLIAM J. KELLY, OF BROOKLYN, NEW YORK, ASSIGNOR OF ONE-THIRD TO HARRY I. BERNHARD, OF BROOKLYN, NEW YORK.

PROCESS OF MAKING SHOES.

Application filed June 18, 1920. Serial No. 389,824.

To all whom it may concern:

Be it known that I, WILLIAM J. KELLY, a citizen of the United States, residing at the city of New York, borough of Brooklyn, county of Kings, and State of New York, have invented a certain new and useful Process of Making Shoes, of which the following is a specification.

This invention is a process of making shoes wherein I utilize an insole of a novel character.

According to my present invention the insole is imposed upon a last, and the upper is lasted for the marginal portion of said upper to lie within a channel of the insole, said channel constituting a line of division between the body portion of the insole and a protuding marginal flap of said insole. Concurrently with the lasting operation, the marginal portion of the upper, and an inner edge portion of a welt are attached to the free portion of said marginal flap, whereby the edge of the upper, together with the fastening means between the upper and the welt, with the marginal flap are adapted to be covered by the marginal portion of the insole in such a manner that said edge of the insole relieves the fastening means from undue strain. The next step in the procedure consists in attaching an outsole to the protuding edge portion of the welt, the attaching means for the outsole being exterior to the attaching means whereby the upper and welt are fastened to the insole.

A shoe produced in accordance with my invention possesses pronounced functions and advantages, among which are (a) the seam by which the upper and welt are fastened to the insole is protected by the edge of said insole in a manner to relieve the seam from undue strain and this minimizes that tendency of the seam to rip; (b) the outsole when worn can be removed from the welt without disturbing the attachment of upper and welt to the insole so that the shoe remains intact during the operation of re-soled it by a cobbler, and (c) the inner surface of the shoe and the top face of the insole remain in a smooth condition so as to be worn with comfort.

Other functions and advantages of the invention will appear from the following

description taken in connection with the drawings, wherein—

Figure 1 is a plan view of an insole to be utilized in the procedure of my invention. 55

Figure 2 is a cross section through said insole.

Figure 3 is a cross section illustrating the operation of sewing a lasted upper and a 60 welt to the channeled margins of the insole, and

Figure 4 is a cross section showing the stitching operation whereby an outsole is 65 sewed to the welt.

In carrying my invention into practice I employ any one of the forms of insole of the character disclosed more particularly in my copending application filed even date herewith, one form of said insole being represented in detail in Figures 1 and 2 of the accompanying drawings, wherein A is the body member of said insole, B is the marginal member protruding for an appreciable distance from the edge of said body member, and C is the channel which extends inwardly from the edge of the body member and which channel constitutes a line of division between the body member and the marginal member at the edge of said insole. 70 In the form of insole shown, the marginal member B is formed by a layer of material positioned in contact with the under face of the body member, and the two pieces of material A, B, are permanently attached by a seam D positioned rearwardly from or within the edge of member A so as to leave free the protruding marginal member and which seam at the same time leaves or provides a space constituting the inwardly 75 extending channel at the edge of said insole. 80

The insole is, as usual, imposed upon a last, with the top face of said insole in contact with the last and so as to leave the marginal member or flap B free from contact 90 with said last.

An upper E is now lasted so that the marginal portion of the upper is caused to extend into the channel C of said insole.

Concurrently with the operation of lasting the upper, I proceed to attach the margin of the upper and the inner edge portion of a welt F to the insole and within the channel C thereof. Said attachment of the 100

upper and the welt to the insole is performed at one operation, at which time the margin of the upper and the inner edge of the welt are sewed to the marginal member or flap B by a seam G in such manner that the edge of the upper, the edge of the welt, and the seam are within the channel C, see Figure 3. The seam G is adapted to be covered by the edge or margin of the body member A of the insole, and when the shoe is worn the pressure of the foot upon the margin of the insole presses said margin upon the seam, with the result that the seam is relieved from undue strain and there is a minimum tendency of the seam to rip or tear.

After stitching the upper and welt to the flap or marginal member of the insole, it is preferred to fill in the space over the insole by a filling or composition, as indicated at H in Figure 4, and thereafter an outsole I is attached to the welt, preferably by sewing said outsole to the welt, the resulting seam J being separate from the seam G by which the upper and the welt are attached to the marginal portion of said insole.

The edge of the upper is encased within the channel of the insole, together with the inner edge of the welt and the seam G, but the welt extends outwardly from the upper and from the marginal flap of the insole, thus positioning the welt for the application of the outsole, the surface of the shoe being leveled by the composition H applied to the insole so that the outsole has a firm contact with and bearing against the shoe. The seam J which attaches the outsole to the welt is independent of the seam G and is positioned exteriorly thereto, as a result of which the outsole can be detached without affecting the seam G, whereby the upper, welt and insole remain in a connected condition and the shoe minus the torn off outsole remains intact, thus facilitating the operation of re-soling the shoe by a cobbler.

It will be understood that I reserve the right of performing in the usual way the operation of lasting an upper so that the margin thereof is adapted to lie within the channel of the insole; but economy of labor, and consequently a reduction in cost of manufacture, is attained by performing the operation of lasting the upper concurrently with the step of attaching the upper and the welt to the insole, said simultaneous or concurrent attachment of the upper and the welt to the insole being conducted in a manner to encase within the channel of the insole the edge of the upper and the inner edge of the welt. As stated, the attachment of the upper and the welt to the marginal member or flap of the insole is performed usually by stitching, although other equivalent modes of attachment, such as stapling, may be employed.

It is to be noted that the attachment of the upper and the welt to the insole concurrently with the step of lasting the upper has a tendency to deflect the welt from the position it occupied normally with reference to the upper upon the completion of the shoe; and after the stitching is performed the welt is "beaten out" in the usual manner and by appropriate means so as to position said welt for the attachment of the outsole.

By reference to Figures 3 and 4 of the drawings it will be noted that the face of the insole along the edge portion thereof is in contact with the inner surface of the upper beginning at or about the line where the upper rises from the lower edge of the insole, and continuing to the top edge of the insole, said marginal portion of the insole or the top flap thereof being positioned to cover the edge of the upper, the seam G and the inner edge of the welt. This contact between the edge of the insole with the upper, together with the covering of the edge of the upper and the seam by the marginal part of said insole, performs to good advantage the important function of relieving the seam from undue strain so that it does not rip.

It is apparent that the marginal flap or member B may be composed of waterproof material, and when an insole with such waterproof flap or member is incorporated in a shoe the seam G is protected, at least to a material extent, from the accession of moisture during rainy weather, hence it follows that by my invention a substantially wet proof shoe is obtained.

Having thus fully described the invention what I claim as new and desire to secure by Letters Patent is:

1. In the art of making shoes, the process which consists in providing an insole with a protruding lip and with a channel which extends inwardly from the edge of said insole, lasting an upper for the marginal portion thereof to be received within the channel of said insole, attaching the upper margin and a welt to said lip of the insole for said lip to extend outwardly from the line of attachment of the upper and welt thereto, placing an outsole on the welt and over the lip to encase the lip between the outsole and the welt, and attaching the outsole to said welt.

2. In the art of making shoes, the process which consists in providing an insole with a protruding lip and with a channel which extends inwardly from the edge of said insole, lasting an upper for the marginal portion thereof to be received within the channel of said insole, sewing the upper margin and a welt to the lip for the edge of said insole to lie over the seam and for said lip to extend outwardly from the seam and into

contact with the welt, positioning an outsole into contact with the welt and to encase said lip between the welt and the outsole, and sewing the outsole to the welt.

5. 3. In the art of making shoes, the process which consists in imposing upon a last an insole provided with a lip the free portion of which protrudes beyond the edge of said insole and free portion of which is separated from the body of the insole by a channel which extends inwardly from the edge of the insole, lasting an upper for the margin thereof to ultimately be received within the channel of said insole, attaching said upper 10 margin and a welt to said lip for the edge of said insole to lie across the line of attachment between the upper margin and the welt to said lip and for the lip to extend outwardly into contact with said welt, imposing an outsole on the welt to encase the lip between the outsole and the welt, and attaching the outsole to the welt on a line exteriorly to the attachment of the upper to the lip and the welt.

25. 4. In the art of making shoes, the process which consists in providing an insole with a lip the free portion of which protrudes beyond the edge of said insole and which free portion of said lip is separated from the body of the insole by a channel which extends inwardly from the edge of the insole, lasting an upper for the margin thereof to ultimately be received within the channel of said insole, sewing the upper margin and a welt to said lip and for the free portion of said lip to extend outwardly beyond said seam, and sewing an outsole to the welt so as to cover the free portion of said lip and encase the same between the welt and said 40 outsole.

50. 5. In the art of making shoes, the improvement which consists in providing an insole with a lip having a free portion which extends beyond the margin of said insole and which free portion of the lip is separated from the body portion of the insole by a channel extending inwardly from the edge of said insole, concurrently with the lasting of the upper attaching the edge of the upper and the inner edge of a welt to said lip for the free portion of the lip to extend outwardly from the line of attachment between the upper and the welt to the lip, and attaching an outsole to the welt so as to encase the free portion of the lip between said outsole and the welt.

55. 6. In the art of making shoes, the im-

provement which consists in providing an insole with a lip having a free portion which extends beyond the margin of said insole 60 and which free portion of said lip is separated from the body portion of the insole by a channel extending inwardly from the edge of said insole, lasting an upper, and concurrently with said lasting of the upper 65 stitching the margin of said upper and the inner edge portion of a welt to the lip of said insole on a line for the seam to lie within the channel of said insole and for the free portion of the lip to extend outwardly 70 from the seam, and stitching an outsole to the welt so as to encase the free portion of the lip between said outsole and the welt.

7. In the art of making shoes, the improvement which consists in providing an 75 insole with a lip having a free portion which extends beyond the margin of said insole and which free portion of said lip is separated from the body portion of the insole by a channel extending inwardly from the edge 80 of said insole, lasting an upper, stitching the edge portion of the insole and the inner edge portion of a welt to the lip on a line close to the junction of the insole with the lip and for said lip to extend outwardly from the 85 seam, lasting the upper concurrently with said stitching, beating out the welt, and attaching an outsole to said welt so as to encase the free portion of the lip between the 90 outsole and the welt.

8. In the art of making shoes, the improvement which consists in providing an insole with a lip having a free portion which extends beyond the margin of said insole and which free portion of the lip is separated from the body portion of the insole by a channel extending inwardly from the edge of said insole body portion, lasting an upper for the margin thereof to ultimately lie within the channel of said insole and for 100 the upper to contact with the face of the insole along the edge thereof, attaching the marginal portion of the upper and the inner edge portion of a welt to the lip of said insole concurrently with the lasting of the 105 upper, impesing an outsole on the welt to encase the free portion of the lip between the outsole and the welt, and attaching the outsole to the welt independently of the attachment of the welt and upper to the lip. 110

In testimony whereof, I have signed my name hereto this 16 day of June, 1920.

WILLIAM J. KELLY.
